SELF-TEACHING MANUAL FOR TYPEWRITERS

Sidney Siegel, Philadelphia, and John H. Emore, Jr.,
Ambler, Pa., assignors to Stationers' Guild of America,
Philadelphia, Pa., a corporation of Pennsylvania

Filed Jan. 16, 1962, Ser. No. 68,328

Term of patent 14 years

(Cl. D25—1)

FIG.1

FIG.2

FIG. 3

FIG. 4

FIG. 1 is a plan view of the self-teaching manual for typewriters with the perforated cover flap overlying the keyboard, showing my new design;

FIG. 2 is a view similar to FIG. 1 with the perforated cover flap swung to full open position;

FIG. 3 is a perspective view of the self-teaching manual for typewriters of FIG. 2 but with the top cover having the conventional keyboard representation swung to full open condition to expose a special lesson board, and

FIG. 4 is a plan view of FIG. 3 but with the perforated cover flap swung to full closed position over the special lesson board of FIG. 3.

The essential feature of our design resides in the combination of the ringed teaching book disclosed and of the

perforated half flap similarly attached at the lower edge of the bottom cover which hingedly overlies the conventional keyboard representation so as to give a tactile sense of key position to the student as shown.

We claim:

The ornamental design for a self-teaching manual for typewriters, as shown and described.
